JET REACTION AND RETURN FLOW PROPULSION MEANS

Georg S. Mittelstaedt, Brooklyn, N.Y.

Application June 27, 1956, Serial No. 594,160

17 Claims. (Cl. 60—35.6)

This invention relates to engines, including reaction engines, and including jet and turbojet systems. It may be used as a propulsion means for aircraft, marine vessels, vehicles, or other movable objects. It also relates to propulsion in part by reaction of a jet.

The invention relates particularly to the return or reverse flow, which I discovered to be associated with an annularly discharged fluid stream cooperating with a centerplate, which may have any shape, character or form. In the text and claims: By "return flow" or "reverse flow" is also meant forward flow and centripetal flow. By "annular" is also meant any encircling outline or figure. By "centerplate" is also meant any central body, central portion, or any central covering or dividing means.

An object of this invention is to improve reaction engines.

Another object of this invention is to create a simple and practicable form of auxiliary propulsion means in cooperation with the annularly discharged exhaust stream of a jet reaction device.

Another object is to gain motion by utilizing the above mentioned return flow effect.

Another object is to utilize said return flow effect to drive a turbine or other device.

Still another object is to provide cooling and ease and simplicity of installation.

These and other objects will become apparent in the description below, in which characters of reference refer to like-named parts in the drawing.

The drawing shows sectional views of various devices, illustrating the application of the invention, but the invention is not limited to the particular devices illustrated.

Figure 1 shows a rocket type reaction engine, illustrating the application of the invention.

Figure 2 shows a turbojet type reaction engine with an inner turbine and a return-flow operated outer turbine, illustrating the application of the invention.

Figure 3 shows a turbojet type reaction engine having a return-flow operated turbine, illustrating the application of the invention.

Referring in detail to the drawing, Figure 1 shows a rocket type reaction engine, where the numeral 1 indicates the case and 2 the propellant. The numeral 3 indicates an annular exhaust nozzle, 4 a centerplate, 6 shows a return-flow actuated body, and 5 shows a connecting member between centerplate 4 and body 6. The arrows indicate the character and approximate directions of the flow. A indicates the annular flow, B the converged or full flow, and C indicates the return flow which I utilize in this invention to gain motion.

Figure 2 shows a turbojet type reaction engine, where the numeral 1 indicates the case, 7 the compressor, 8 the combustion chamber or flame tubes, and 9 the inner turbine. The numeral 3 indicates the annular exhaust nozzle, 4 a centerplate and 10 a return-flow operated turbine, shown mounted on the same shaft 11 with the compressor 7. The arrows indicate the character and

2

approximate directions of the flow. A indicates the annular flow, B the converged or full flow, and C indicates the return flow which I utilize in this invention to gain motion.

Figure 3 shows a turbojet type reaction engine, where the numeral 1 indicates the case, 7 the compressor, 8 the combustion chamber or flame tubes, 3 indicates the annular exhaust nozzle, 4 a centerplate, and 10 a return-flow operated turbine, shown mounted on the same shaft 11 with the compressor 7. The arrows indicate the character and approximate directions of the flow. A indicates the annular flow, B the converged or full flow, and C indicates the return flow which I utilize in this invention to gain motion.

The annular flow A converges to a full flow B, and in association with centerplate 4 a return flow C is created. I have conducted numerous experiments and I have found that the above defined reverse flow C develops essentially as illustrated and described. I believe that the converging annular fluid stream creates a near vacuum or low pressure pocket at C, and an exterior medium, such as part of the fluid stream is forced into said pocket, thereby creating the reverse flow C.

I propose to utilize the described reverse flow C to impinge on a target surface or body 6, which may have any suitable shape, character or form. Said body 6 is situated rearward of the centerplate 4 and within the return flow region C, said body 6 being preferably smaller in diameter than said centerplate 4. It is evident that the body 6 is located away from the fluid stream portions A and B. It is also evident that said body 6 is located in the path of the described reverse flow C, said reverse flow C impinging on said body 6, thereby creating motion. The target surface for said return flow C may be part of the centerplate or engine structure, and said centerplate may be part of the engine structure.

Such a body 6 may be vanned and have the characteristics of a turbine, and the invention embraces the use of a turbine or related device in cooperation with the defined reverse flow C. In this application of the invention the described return flow C is used to furnish power to operate the turbine 10 which is located rearward of the centerplate 4 and within the return flow region C, said turbine 10 being preferably smaller in diameter than said centerplate 4. The turbine 10 may drive a compressor 7 for furnishing an airstream or other form of compressed air, which may be used in the engine. It is evident that the turbine 10 is located away from the fluid stream portions A and B. It is also evident that said turbine 10 is located in the path of the described reverse flow C, said reverse flow C impinging on said turbine 10, thereby creating rotation and motion.

The described turbine may be attached to any suitable part of the structure. The turbine 10 may be coaxial with the compressor 7, and may be mounted on the same shaft 11 with the compressor 7.

It is part of this invention to utilize this described reverse flow to secure a cooling effect on the turbine or in the propulsion system.

It is to be noted that changes in form and construction may be made without departing from the spirit or scope of the invention.

I claim:

1. A jet reaction and return flow propulsion device, including a combustion chamber, an annular nozzle for leading the exhaust from said combustion chamber to atmosphere, and a centerplate encircled by said annular nozzle, said nozzle discharging an annular fluid stream, said annular fluid stream converging to a full stream and creating a return flow in cooperation with said centerplate, the return flow region lying within the confines of the annular and converging portion of said fluid stream

and between said centerplate and the convergence point of said fluid stream, a turbine situated rearward of said centerplate and in the path of said return flow, said turbine being smaller in diameter than said centerplate, said return flow exerting a pressure on said turbine, thereby creating motion and rotation.

2. A system according to claim 1, a compressor for furnishing an airstream for use in the combustion chamber, said return-flow turbine being connected with said compressor.

3. A system according to claim 2, said turbine having the same shaft with said compressor.

4. A system according to claim 2, an inner turbine located upstream of the terminal of the exhaust nozzle, said return-flow turbine being connected with said inner turbine.

5. A system according to claim 4, said return-flow turbine having the same shaft with said inner turbine and with said compressor.

6. A jet reaction and return flow propulsion device, including a combustion chamber, an annular nozzle, and a centerpiece encircled by said annular nozzle, said nozzle leading the exhaust from said combustion chamber to atmosphere, said nozzle discharging an annular fluid stream, said annular fluid stream converging and creating a return flow in cooperation with said centerpiece, a turbine situated rearward of said centerpiece and in the path of said return flow, said return flow exerting a pressure on said turbine, thereby creating motion and rotation.

7. A system according to claim 6, a compressor for furnishing an airstream for use in the combustion chamber, said return-flow turbine being connected with said compressor.

8. A system according to claim 7, said return-flow turbine having the same shaft with said compressor.

9. A system according to claim 7, an inner turbine located between the nozzle terminal and the combustion chamber, said return-flow turbine being connected with said inner turbine.

10. A system according to claim 9, said return-flow turbine having the same shaft with said inner turbine and with said compressor.

11. In a device of the class described, a combustion chamber, an annular nozzle, and a central part encircled by said annular nozzle, said nozzle leading the exhaust

from said combustion chamber to atmosphere, said nozzle discharging an annular exhaust stream, said annular exhaust stream expanding inward to a full stream and creating a return flow in cooperation with said central part, a means to utilize said return flow to gain motion, said means comprising a target situated in the path of said return flow, said return flow exerting pressure on said target, tending to move said target.

12. A system according to claim 11, said target comprising a body situated in the path of said return flow, said return flow exerting pressure on said body, tending to move said body forward.

13. A system according to claim 11, said target comprising a body rearward of said central part and separated with a space therefrom, a support for said body, said body being smaller in diameter than said central part.

14. A system according to claim 11, said target comprising a turbine situated in the path of said return flow, said return flow impinging on said turbine, thereby creating rotation.

15. A system according to claim 11, said central part having a flat end-surface parallel with the nozzle opening.

16. A propulsion device, including a means to produce a flow, an annular nozzle to discharge said flow annularly, a centerpiece encircled by said annular nozzle, and a body rearward of said centerpiece and separated with a space therefrom, a support for said body, said body being smaller in diameter than said centerpiece, the annular flow expanding inward after discharge from said annular nozzle and creating a return flow in cooperation with said centerpiece, said return flow exerting pressure on said body, tending to move said body.

17. A system according to claim 16, said body being vaned and rotatably mounted.
